UNITED STATES PATENT OFFICE.

WARNER R. BUXTON, OF SPRINGFIELD, MASSACHUSETTS.

KEY-CASE.

1,261,692.

Specification of Letters Patent. Patented Apr. 2, 1918.

Application filed March 13, 1916. Serial No. 83,958.

To all whom it may concern:

Be it known that I, WARNER R. BUXTON, a citizen of the United States of America, residing in Springfield, in the county of 5 Hampden and State of Massachusetts, have invented certain new and useful Improvements in Key-Cases, of which the following is a specification.

This invention relates to key cases and, 10 more particularly, to key cases of improved construction, whereby keys may be held within the case in an advantageous manner.

Key cases have been used, heretofore, and are shown in various forms in the prior art. 15 Commonly, a case constructed along the lines of a pocketbook is used, and the keys are supported within the case upon an ordinary key ring which is held to the case by a suitable stud. In such key cases, the 20 ring is arranged to receive the key with the axis of the eye of the latter disposed parallel, or substantially so, with respect to the case, whereby the key itself is constrained to lie perpendicularly or at least at 25 a wide angle to the case. Moreover, the ring employed permits the keys to bunch in a central mass and, since the keys do not lie flat within the case, the latter is bulged out centrally in an undesirable wad. Other 30 cases for keys have been provided, which employ independent means to receive each key. For example, chains, secured at one end within the case, are provided with means at the other end to receive a key. With such 35 devices, the bunching of the keys within the case is not prevented although the keys may in some instances be constrained to lie flatly against the casing. Moreover, the keys are free to shuck back and forth and are not 40 securely retained within the casing so that they may and frequently do shake out of the case. Furthermore, the keys are not quickly and readily accessible and the selection of any desired key is not particularly 45 convenient.

An object of this invention is to provide a key case, arranged to receive a plurality of keys, which is so constructed that each key is held flatly against the casing, is separated from each other key to prevent bunching, and is positively retained in position against longitudinal displacement whereby the keys cannot shuck around within or be shaken out from the casing.

55 Another object of the invention is to pro-

vide in a key case of the class described, a plurality of independent devices, each constructed to receive a key with the axis of the eye of the latter normal to the case, whereby the keys have a tendency to lie 60 flatly against the case, and a common pivotal connection for said devices, whereby when the case is opened, the devices may be swung through a limited angle to throw the keys out of the case, said devices being positively 65 held against swinging when the case is closed.

Other objects and advantages will appear in the detailed description to follow and in the annexed claims.

70 For the purpose of illustrating one way in which the invention may be practised, one preferred embodiment thereof is shown in the accompanying drawings, in which—

Figure 1 is an elevational view of the key 75 case with the flaps opened;

Fig. 2 is a similar view with the flaps closed;

Fig. 3 is a sectional view taken on the line 3—3 of Fig. 2 and looking in the direction 80 of the arrows;

Fig. 4 and Fig. 5 are fragmentary sectional views taken on the lines 4—4 and 5—5, respectively, of Fig. 1 and looking in the direction of the arrows; and

85 Fig. 6 is a view taken similarly to Fig. 5 showing a modification.

Referring to these drawings, the case itself comprises a single piece of suitable material, such as leather, or the like, which 90 is foldable along the lines 1—1 of Fig. 1, whereby a back 2 and two movable flaps 3 are provided. The latter are foldable in overlapping relation over the back 2 in an obvious manner, and any suitable means 95 may be provided to hold the flaps 3 together, such as a male fastener 4 on one flap and a female fastener 5 on the other flap, as shown in Figs. 1 and 3.

Secured to the back 2 by eyelets 6 is a 100 frame 7 of flat metal which is formed with two spaced ears 8 struck up therefrom, as shown in Figs. 1, 3, and 4. Extending between ears 8 and fixed thereto by any suitable means, such as riveting, for example, 105 is a pivot rod 9 which is arranged adjacent the top of back 2 and in parallel relation therewith. Loosely mounted on rod 9 are a plurality of snap hooks 10 which normally depend from rod 9, as shown, and are 110

adapted to receive keys, such as shown at 11 in Figs. 1 and 2. A sleeve 12 loosely mounted on rod 9 is interposed between each pair of hooks 10 to effectually hold the latter 5 in longitudinally spaced relation. Any other suitable means may be employed to hold the hooks 10 in proper spaced relation. For example, strips of a width equal to sleeves 12 may be struck up from plate 7, 10 as shown in Fig. 6 at 15, to lie between the hooks and hold them from longitudinal movement on rod 9.

It is to be particularly noted that each hook 10 is arranged to support a key from 15 the eye thereof with the axis of the latter in normal relation to the back 2, whereby the keys have a tendency, inherent from this arrangement, to lie flatly against back 2. Moreover, the hooks 10 are so spaced that 20 keys on successive hooks must overlap, as shown in Figs. 1 and 2, but this overlapping of the keys does not prevent the latter from being disposed in parallel relation to back 2. The overlapping of the keys as described is 25 of advantage because the combined thickness of the overlapping keys is ordinarily approximately equal to the breadth of the lower portion of hooks 10. Thus, when the flaps 3 are lapped over one another and fastened, the flaps bear against the outermost portions of hooks 10 and the outermost keys 11, so that the folded case is substantially of uniform thickness and of generally flat form. By this construction, the keys are 35 frictionally held in place and cannot freely shuck around within the case.

The use of the pivoted hooks 10 effectually prevents the keys from being shaken out of the case for the hooks are held against 40 movement on pivot 9 by the pressure of flaps 3. When, however, the latter are opened the hooks 10 may swing through substantially one hundred and eighty degrees to the position indicated by dotted lines in 45 Fig. 5, wherein the keys 11 will be thrown out of the case. The keys may be conveniently thrown out of the latter, if the open case with the keys facing upwardly is held in one hand and given a quick downward 50 swing. It is also to be noted that any desired key can be quickly and conveniently removed independently of the others and that the selection of any desired key for use is made easy and convenient by the fact that 55 the keys are spread out within the casing and maintained in this position by the spaced parallel hooks.

Thus, an improved key case has been provided which is characterized by a positive 60 retention of the keys within the case in overlapping relation with respect to one another and in parallel relation to the casing, whereby movement of the keys within the latter is prevented and the folded case is 65 of flat and substantially uniform thickness.

It is recognized that changes may be made in the structure herein described for illustrative purposes without departing from the scope of the invention which is defined by the appended claims rather than by the foregoing description of a preferred form. 70

What I claim is—

1. A case for keys or the like, comprising, a supporting strip, a plurality of devices pivotally supported from the strip, each of 75 said devices arranged to removably support a key and constrained to swing in a single plane, foldable flaps provided on said strip, and means to removably secure said flaps together in overlapping relation over said devices to hold the latter from swinging in said plane.

2. A key case, comprising, a supporting strip, a plurality of devices directly pivoted to the strip, each of said devices being constrained to move in a definite path and adapted to support a key with the axis of the eye of the latter disposed in normal relation to said strip, whereby the keys may lie flat against the latter, flaps formed on 90 said strip arranged to be folded in overlapping relation over said keys and devices, and means to removably secure the flaps together.

3. A key case, comprising, a supporting member, a plurality of key receiving devices pivotally supported in longitudinally spaced relation thereon, each of said devices being constrained to swing in a single plane, flaps formed on said member and arranged to be 100 folded together in overlapping relation to hold said devices from pivotal movement, and means to removably secure the flaps one to the other, all constructed and arranged so that keys may be positively held flat 105 against said member in spaced relation, and so that said devices may be turned on their pivot when the flaps are open to throw the keys into position for convenient use.

4. A key case, comprising, a flexible supporting member, a pivot rod secured to said member, and a series of snap hooks mounted on said rod in longitudinally spaced relation and arranged for limited turning movements, each of said hooks adapted to support 110 a key, the end portions of said member arranged to be folded in overlapping relation over said hooks and removably fastened together, all constructed and arranged so that movement of the hooks is prevented when 120 the flaps are fastened together.

5. A key case, comprising, a flexible supporting member, a pivot rod supported thereon, a series of snap hooks, mounted on said rod in longitudinally spaced relation, 125 said hooks adapted to receive keys and to support the latter in parallel relation to said member, the end portions of the latter being foldable in overlapping relation over said hooks and keys, and means to remova- 130

bly secure said end portions in their folded position, all constructed and arranged so that keys may be held in spread out relation within said member against free movement 5 therein.

6. A key holder, comprising, a supporting member adapted for attachment to a fold-

able inclosing case, and a plurality of key supporting devices directly pivoted to said member in longitudinally spaced relation, 10 said devices being arranged to swing through a limited arc and being constrained to swing in a single plane.

WARNER R. BUXTON.
